UNITED STATES PATENT OFFICE

2,338,553

PAY ROLL BOARD

Lois K. Straus, Great Neck, N. Y., assignor to The Shaw-Walker Company, Muskegon, Mich., a corporation of Michigan

Application October 30, 1942, Serial No. 463,986

6 Claims. (Cl. 282—29)

This invention relates to a novel and improved pay roll board and consists of the matters hereinafter described and more particularly pointed out in the appended claims.

Payments for wages or salaries to employees are now subject to many deductions, all payable at the source—that is to say, by the employer. All such deductions are required to be reported to the Federal Government by the employer, to justify and explain the difference between the gross amounts set up for pay roll and the reduced amounts actually paid by the employer to his employees. As is well known, this has placed a great burden of expense on business, both in the matter of employing additional help and also in the added expense incurred for printed forms adapted for the many reports.

The object of the invention is to reduce the amount of work necessary to produce the office records required to present in easily accessible form the items requisite to fill out the Government statement which must be filed by the employer in his own and in his employees' behalf at stated periods during the year.

The specific object of the invention is to provide a pay roll board having a straight edge extending transversely thereof near one end; having a scale extending parallel to said straight edge; and having means for clamping to said board a horizontally and vertically ruled pay roll sheet with its horizontal ruling in right angular relation to said straight edge and in register with said scale, with which a similarly ruled employee's earnings sheet and an employee's weekly or monthly pay slip may be superposed in predetermined relation, so that a single writing on the pay slip for each employee will produce not only the pay roll sheet for all the employees listed thereon, but also an employee's earnings sheet for each employee and his weekly or monthly pay slip, showing in each case the gross pay, the several deductions and to whom paid, the net balance to be paid to the employee, the date of the payment, and the employee's clock number.

The advantages of the invention will appear more fully as I proceed with my specification.

In the drawings:

Figure 1 indicates a perspective view of the novel pay roll board.

Figure 2 is a perspective view of a ruled pay roll sheet adapted for use on said pay roll board.

Figure 3 indicates a ruled employee's earnings sheet, with the spacing of its ruling corresponding to the ruling of said pay roll sheet.

Figure 4 is a plan view of an employee's pay slip.

Figure 5 is a partial plan view of the pay roll sheet and employee's earnings sheet with the employee's pay slip applied to the monthly pay roll sheet.

Figure 6 is a top plan view on an enlarged scale of the pay roll board of Figure 1 shown with the pay roll sheet and employee's earnings sheet, with an interposed carbon clamped in operative position to said pay roll board.

Figure 7 is a transverse sectional view of said pay roll board in a plane indicated by the line 7—7 of Figure 6.

Figure 8 is a sectional view in the plane of the sectional view of Figure 7, but on an enlarged scale, showing the clamping and scale members held down on the board in full lines, with the clamping member shown in dotted lines in raised position.

Figure 9 is a fragmentary side elevation of Figure 8 looked at in the direction of the arrow 9 in Figure 8.

Figure 10 is a like section, with the clamping and straight edge members in a position of partial withdrawal from the board as when removing or introducing a pay roll sheet.

Figures 10^a, 11, 12 and 13 are perspective views which will be described more fully in the specification.

Referring now to the embodiments of the invention as illustrated in the drawings: 20 indicates the pay roll board. Said board is made of any suitable material which is of sufficient rigidity to present and maintain a flat, unwarped surface, preferably wood or other fibrous material. At laterally spaced intervals adjacent one end of the board 20 the board is provided with apertures 21 adapted to receive threaded thimbles 22 (see Figures 7, 8 and 10). The upper ends 22^a of said threaded thimbles project through the board and above its top surface. At their bottom ends each of said thimbles is provided with a laterally extending flange 22^b which is inset into the bottom of the board and secured thereto by a screw 22^c. The upwardly projecting ends 22^a of said thimbles provide studs to engage in similarly spaced holes 23^a, 23^b in a ruled pay roll sheet 23 and hold said sheet against lateral displacement on the board 20.

24 indicates an angle plate extending along the end of the board adjacent the thimbles 22. Said angle plate has a wide horizontal flange 24^a adapted to rest upon the top surface of the board 20. Said flange is provided with apertures 24^b

through which the upwardly projecting ends 22^a of the thimbles 22 extend. A vertical flange 24^c of said angle plate extends along and is engaged against the end 20^x of the board 20. The edge 24^d of the horizontal flange 24^a presents a straight edge rising from the board and extending transversely thereof.

25 indicates a clamping member which is hinged to the vertical flange 24^c of the angle plate 24 as shown in Figures 8 to 10, inclusive, in manner to be swung upon a horizontal axis extending parallel to the plane of the board 20. Said hinging as shown is provided at suitable lateral intervals by pairs of brackets 26, 27 secured, respectively, to said clamping member 25 and to said flange 24^c of the angle plate 24, each with associated pairs of ears 26^a, 27^a held together by a pintle pin 28 (see Figure 9). A coiled spring 29 in each case normally holds the clamping member when in proper position, as shown in Figure 8, yieldingly engaged with the top surface of the board 20.

The clamping member extends laterally beyond the straight edge 24^d of the angle plate 24, and is provided with a depending shoe 25^a which extends adjacent to and parallel with the said straight edge 24^d. A numerical scale 30 extending transversely of the board and disposed parallel to the straight edge 24^d is indicated by suitable etching or otherwise on the beveled edge surface of the shoe 25^a of the clamp 25, as shown in Figures 6 and 8.

The angle plate 24 and the clamping member 25 hinged thereto provide an assembly which may be engaged upon or removed from the board by the engagement or disengagement of the upper ends 22^a of the thimbles 22 with the holes 24^b in the angle plate 24 (see Figures 8 and 10). A bolt or screw 31 adapted for engagement in the threaded thimble 22 and having a knurled head 31^a for the purpose is adapted to secure said assembly in place, as shown in Figures 6 and 8.

The pay roll sheet 23 is ruled horizontally to provide spaces 32 extending horizontally across the sheet for the recording of the various items associated with each employee whose name appears on the sheet. It is ruled vertically to provide a column 33 of a width to receive said names. A narrow vertical column 34 with numerals 34^a in arithmetic succession in the spaces 32, presents the numerical order in which the names of employees appear on the sheet. Said spaces 32 on the sheet 23 are made equal to the vertical spaces on the scale 30 of the pay roll board (see Figure 6).

The holes 23^a in the sheet 23 are disposed in a vertical line at right angles to the horizontal alignment of said spaces 32. To one side (the left-hand side as shown in Figure 6) of the line of holes 23^a, 23^b, the pay roll sheet 23 is ruled vertically to provide columns in which to enter the various items involved in the determination of the net payment due an employee for an interval of settlement, as a week or the like, after deduction of all the items payable at the source, that is to say, by the employer.

First, there is a column headed Total hours. In this column will be entered the actual number of hours which the employee has put in during the week. These entries are taken from vertically ruled columns for each day of the week headed Hours worked, with a sub-heading Total, which follow column 34 on the sheet.

After the said column headed Total hours appear three vertical columns under a general head-

ing Earnings, with sub-headings for each column—Regular, Overtime and Gross pay. Following the columns headed Earnings are columns headed Deductions, with sub-headings for each column indicating the nature of such deductions. In the first column as shown appear the initials F. O. A. B., being the most familiar deduction, namely, Federal old age benefit or Social security. The following columns will be headed by other initials to indicate hospital deductions, group insurance deductions, dues deductions, and the like, as may be necessary. Then follow three final columns. The first is headed Net pay. In this will be entered, in line with the name of the employee in column 33, the amount of the net pay. The second column is headed Day and month in which will be written in the same line the date on which ends the week to be paid for. The last column is headed Number. In this will be entered the employee's clock number or other number to identify him.

35 indicates the employee's earnings sheet. Said sheet is of a width to include on the same scale the vertical columns of the pay roll sheet 23 beginning with the column headed Total hours and ending with the column headed Number on the pay roll sheet, and is provided with like headings. Above said headings the sheet is provided with space for the name of the employee, the year, the employee's clock number, and any other items required by the particular business carried on by the employer. Laterally beyond the columns headed Total hours and Number the employee's earnings sheet 35 is provided with vertical columns each ruled transversely to provide vertically disposed spaces in which appear printed numerals 35^a in numerical succession from 1 to 30, inclusive, indicating in numerical succession the intervals of payment—as weeks, for example.

36 (see Figures 4, 5 and 6) indicates the employee's pay slip. Said pay slip is ruled to provide a single horizontal space 36^a running lengthwise of said pay slip and divided under headings 36^b beginning Total hours, Earnings, etc., and ending Number, in manner corresponding to the like headings on the employee's earnings sheet 35 and the pay roll sheet 23. (See Figures 10^a and 11.)

At one end of said pay slip 36 is provided a short extension 36^c with a line of weakening 36^d dividing it from the body of the slip. In line with the horizontal space 36^a and at its ends are cut a circular opening 36^e crossing the line of weakening 36^d and a half circular opening 36^f at the other end of the horizontal space 36^a.

Above the headings 36^b is provided a space to receive the name and number of the employee and other data required. On the reverse face of the pay slip 36 back of the horizontal space 36^a on its obverse face is a band of transfer material 36^g; and on said reverse face above the headings and back of the space on its obverse face which is intended to receive the employee's name and number, is a band of transfer material 36^h.

65 The operation of the device is as follows: A pay roll sheet 23 is placed on the pay roll board 20. To do this the thumb bolts 31 are first unscrewed from the threaded thimbles 22, and the assembly of angle plate 24 and clamp 25 are raised as in Figure 10 to permit the holes 23^a, 23^b in the pay roll sheet to be engaged upon the ends 22^a of the thimbles 22 projecting above the board. The thumb bolts 31 are then re-engaged with the threaded thimbles 22 and the said assembly is screwed down upon the board to bring the clamp-

ing shoe 25^a into clamping engagement with the pay roll sheet 23. Then or prior thereto the names of the employees are put down in the column 33 provided therefor, each opposite to an associated numeral 34^a in the column 34 of said sheet. The said sheet is now in position with all of its horizontal spaces enumerated in the column 34 in horizontal alignment with like numbered spaces on the scale 30 of the board and in right angular disposition with reference to the straight edge 24^d.

An employee's earnings sheet 35 bearing one of the names in the column 33 of the pay roll sheet 23 (John Doe, for example) is then selected. An employee's pay slip 36 is applied to the left-hand edge of the said sheet 35 by folding down the extension 36^c on the line of weakening 36^d and then bringing said extension back against the bottom face of the lateral margin of the sheet 35. The pay slip 36 is then moved up or down along the sheet 35 until it is brought into register with that one of the numerals 35^a corresponding to the ordinal number of the week for which the payment is to be made. The week in this case is number 5 (see Figure 6).

The employee's earnings sheet 35 with the employee's pay slip 36 thus applied is then brought to position with its right-hand edge in engagement with the straight edge 24^d on the board, and with the horizontal space 36^a on the pay slip 36 and the exposed numeral 5 on the employee's earnings sheet 35 in alignment with the numeral 7 on the scale 30, which numeral is the one associated at the left in the column 34 on the pay roll sheet 23 with the name John Doe. In bringing this about, the clamp member 25 is raised to permit the insertion of the sheet in the manner described, and also the insertion of a carbon sheet 37 (see Figure 6) between said employee's earnings sheet 35 and the pay roll sheet 23.

The various items under the headings appearing in superposed relation on the pay roll sheet 23, the employee's earnings sheet 35 and the employee's pay slip 36 are then written in under the proper headings on said pay slip 36 and are thus reproduced respectively upon the employee's earnings sheet 35 and upon the pay roll sheet 23 in the one writing.

This operation is repeated for each and every employee appearing on the pay roll sheet in the column 33. Thereupon the addition of all the items on the pay roll sheet appearing in the column headed Net pay will give the cashier or other paymaster, as a bank, Brink's Agency or the like, the total amount of cash necessary to pay to each of the several employees on the pay roll sheet 23 the net amounts appearing on their respective pay slips 36.

In the case of larger businesses where more than one pay roll sheet is required to include all the employees, the additional pay roll sheets supplied are treated successively in the same manner as that hereinabove described for the first pay roll sheet, successive pay roll sheets bearing columns 34 with numerals in ordinal succession to those of the first sheet.

When payments to the employees are to be made by cash, envelopes are provided to receive the pay slip and also the cash covering the net amount of the payment due, as shown by said pay slip. An envelope for this purpose is shown in Figures 12 and 13. 40 indicates said envelope. It consists of a flat tube 41 closed at one end by a narrow flap 42 and provided at its other open

end with a longer flap 43 which has a band of sealing material 44 indicated by dotted lines in Figure 13. Intermediate its lateral edges is a narrow slot 45 in the body of the envelope. The envelope is wide enough to receive the pay slip when folded upon itself, with the extension 36^c folded under as shown in Figure 13.

To prepare the envelope, the pay slip 36 is applied to the face of the envelope, with the extension 36^c turned under its left-hand edge and with the part of the pay slip having the space for the name and number near the top, as shown in Figure 10^a. The name of the employee and his clock number are then written on the pay slip, 15 the same being reproduced on the face of the envelope, as shown in Figure 12, by the carbon means 36^h on the back of the pay slip. The pay slip is then ready for the operations in association with the employee's earnings sheet and the pay roll sheet as heretofore described.

After the said operations are performed on the pay slip, it is folded and is inserted into the envelope as shown in Figure 13. The net amount of money to be paid to the employee is exposed 25 by the slot 45 in the envelope. When the envelopes for the employees listed on the pay roll sheet go to the cashier, bank or Brink's Agency or other pay agent, the agent puts into the envelope the amount of money designated on the 30 pay slip as exposed through said slot, and seals the envelope. At this time he is not concerned with the employee's name or number of the employee to whom this amount of money is to go. However, the name and number of the employee 35 appear on the face of the envelope.

When the money for the total amount of the pay roll is in the hands of the distributing agent, said agent delivers to each employee in each case a sealed envelope in return for a metal disc, top 40 of a clock card or other identifying means bearing a number identical with the number on said envelope. No other receipt is received or required.

Whereas in describing the invention I have referred to several details of construction and arrangement of parts and have described its use as specifically applied to pay roll sheets, employee's earnings sheets and pay slips, it will be understood that the invention is in no way limited thereto except as may be pointed out in the appended claims.

I claim as my invention:

1. In combination, a writing board, laterally spaced studs projecting above said board near one end thereof, a straight edge member and a clamping member extending transversely of said end of said board, said straight edge member being apertured to engage said studs above said board, means for hinging said clamping member 55 to said straight edge member, said clamping member having a shoe disposed beyond said straight edge member, extending parallel to said straight edge and to said studs, the straight edge member and clamping member being removable as an assembly from said board, and means for removably securing said assembly to said studs.

2. In combination, a writing board, laterally spaced studs projecting above said board near one end thereof, a straight edge member and a clamping member extending transversely of said end of said board, said straight edge member consisting of an angle plate having a horizontal flange with a straight edge and being apertured to engage said studs above said board, and a vertical flange to engage the end of said board,

means for hinging said clamping member to said vertical flange of the straight edge member, said clamping member having a shoe disposed beyond said straight edge, extending parallel to said straight edge and to said studs, the straight edge member and clamping member being removable as an assembly from said board, and means for removably securing said assembly to said studs.

3. In combination, a writing board, laterally spaced threaded thimbles fixed to said board with their ends projecting above said board near one end thereof, a straight edge member and a clamping member extending transversely of said end of said board, said straight edge member being apertured to engage said thimbles above said board, means for hinging said clamping member to said straight edge member, said clamping member having a shoe disposed beyond said straight edge member, extending parallel to said straight edge and to said thimbles, the straight edge member and clamping member being removable as an assembly from said board, and thumb bolts adapted for threaded engagement with said thimbles with their heads engaged against said straight edge member.

4. In combination, a writing board, laterally spaced threaded thimbles fixed to said board with their ends projecting above said board near one end thereof, a straight edge member and a clamping member extending transversely of said end of said board, said straight edge member consisting of an angle plate having a horizontal flange with a straight edge and being apertured to engage said thimbles above said board, and a vertical flange to engage the end of said board, means for hinging said clamping member to said vertical flange of the straight edge member, said clamping member having a shoe disposed beyond said straight edge, extending parallel to said straight edge and to said thimbles, the straight edge member and clamping member being removable as an assembly from said board, and thumb bolts adapted for threaded engagement with said thimbles with their heads engaged against the horizontal flange of said straight edge member. 45

5. In combination, a writing board, threaded thimbles fixed to said board adjacent one end thereof and having ends projecting above said board, an assembly comprising an angle plate having a flange adapted to engage the end of said board adjacent said thimbles and a flange apertured to engage the upper ends of said thimbles and to bear upon said board, a clamping member yieldingly hinged to said angle plate, said second named flange of said angle plate being formed to provide a straight edge and said clamping member being formed to provide a shoe disposed adjacent to and extending parallel to said straight edge, a scale extending parallel to said straight edge, and thumb bolts adapted for engagement with said threaded thimbles, said clamping member being apertured to permit the passage of the heads of said thumb bolts for contact with said angle plate to hold it and the shoe of said clamping member in engagement against the top of said board.
- 10 6. In combination, a writing board, threaded thimbles fixed to said board adjacent one end thereof and having ends projecting above said board, an assembly comprising an angle plate having a vertical flange adapted to engage the end of said board adjacent said thimbles and a horizontal flange apertured to engage the upper ends of said thimbles and to bear upon said board, a clamping member yieldingly hinged to the vertical flange of said angle plate, said horizontal flange of said angle plate being formed to provide a straight edge and said clamping member being formed to provide a shoe disposed adjacent to and extending parallel to said straight edge, said clamping member having a scale extending parallel to said straight edge, and thumb bolts adapted for engagement with said threaded thimbles, said clamping member being apertured to permit the passage of the heads of said thumb bolts for engagement with the horizontal flange of said angle plate to hold it and the shoe of said clamping member in engagement against the top of said board.
